UNITED STATES PATENT OFFICE.

RUDOLPH SIEBERT, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,866.

Specification for Design.

Patented Nov. 7, 1916.

Application filed August 30, 1916. Serial No. 117,812. Term of patent 3½ years.

To all whom it may concern:

Be it known that I, RUDOLPH SIEBERT, a citizen of the United States, and a resident of the city of Rochester, county of Monroe, and State of New York, have invented a new, original, and ornamental Design for Buttons, of which the following is a specification.

My design is represented in the accompanying drawing, in which;

Figure 1 is a plan view of a button showing my new design. Fig. 2 is a side elevation. Fig. 3 is a section on line 3—3 of Fig. 1.

The button is circular in shape, the central portion of the upper surface of the button is provided with two concentric circular ridges which are flat upon their upper surfaces and which upper surfaces lie in parallel planes.

The cavities formed in the center of the inner circle and between the inner and outer

circle, are substantially the same depth throughout. The outer portion of the upper surface is conical in shape and extends from the outer periphery to the base of the outer circle. That portion of the upper surface not included in the circular ridges is provided with contrasting colors, and the upper surfaces of the ridges are in solid colors. The lower surface of the button is smooth and is formed with a central projection as shown.

I claim:

The ornamental design for a button substantially as shown and described.

In witness whereof I have hereunto set my hand at the city of Rochester, in the county of Monroe and State of New York, this 25th day of August 1916.

RUDOLPH SIEBERT.

In the presence of—

W. D. HULBURT,
EARL A. WELLER.
